FLUID PRESSURE CONTROL APPARATUS
FOR FREE PISTON MACHINES

Ralph T. Whitney, Irwin, Pa., assignor to Westinghouse Air Brake Company, a corporation of Pennsylvania

Application December 9, 1947, Serial No. 790,547

4 Claims. (Cl. 60—14)

1

This invention relates to control apparatus for free piston machines of the type usually embodying two opposed piston assemblages operable by expansion of hot gases generated in a combustion chamber common to both assemblages, for effecting pumping or compression of a gas such as air.

In the copending application of A. J. Bent, Serial No. 762,771, filed July 22, 1947, now Patent No. 2,608,052, and assigned to the assignee of the present application, there is disclosed control apparatus for controlling a free piston machine of the above type, in which each piston assemblage comprises a power piston, an air compressor piston, and a direct bounce piston secured together. By expansion of hot gases in a combustion chamber during normal running of the machine the power pistons of both piston assemblages are forced outwardly, causing air to be compressed in and displaced from respective chambers at one side of the air compressor pistons and to be compressed in respective direct bounce chambers at the end of the direct bounce pistons. By expansion of the air compressed in the direct bounce chambers during the outward stroke of the assemblages, a return inward stroke of said assemblages is effected, advancing the air compressor pistons in the direction of respective reverse bounce chambers at their opposite sides, and causing the power pistons to move in the direction of the common combustion chamber for compressing combustion air supplied thereto during the previous outward stroke.

In the abovementioned application, means are disclosed whereby during running of the free piston machine the reverse bounce chambers are continuously open to a source of fluid under pressure for pressurizing said chambers. Also during starting and warm-up of the machine, the reverse bounce chambers remain open to the source of fluid under pressure, but normally closed vent valve means are opened at this time which vent said chambers to the atmosphere to thereby reduce pressure of fluid therein. It will therefore be apparent that during starting and warm-up considerable fluid under pressure from the source may be lost to the atmosphere via the reverse bounce chambers; for sake of economy this loss of fluid under pressure is undesirable. It is therefore a prime object of the invention to provide means for preventing such loss.

According to this object, I provide a fluid pressure operable valve device associated with the control apparatus disclosed in the aforementioned application which is automatically operable to cut off communication between the source of fluid

2

under pressure and the reverse bounce chambers when the vent valve means are open, and to re-establish said communication when said vent valve means are closed, for thereby preventing the above described unnecessary loss of fluid under pressure from said source.

Other objects and advantages of the invention hereinafter will become obvious from the following more detailed description thereof.

10 In the accompanying drawing; Fig. 1 is a diagrammatic view of a free piston machine with a portion of the control apparatus therefor, in which apparatus the invention is embodied; and Fig. 2 is a partial plan view of an operator's control device shown in elevation in Fig. 1.

Description

The free piston machine and the control apparatus therefor embodying the invention may be substantially the same as that fully disclosed and described in the aforementioned copending application, to which reference may be made, in view of which that portion of said control apparatus directly pertinent to the invention and necessary for a clear understanding thereof is shown in the drawing in detail, for detailed description of other devices described briefly in the present application and not shown in the drawing, reference may be made to the aforementioned application.

As shown in the drawing, the reference numeral 1 designates a free piston machine of the gas generator type comprising a casing containing two opposite, coaxially arranged power pistons 2, 2a slidably mounted therein. Between the respective ends of the two power pistons 2, 2a is formed a combustion chamber 3 which is common to both. By burning fuel supplied from a nozzle 4 in combustion chamber 3, hot expandable combustion gases are generated for driving the power pistons 2, 2a through power strokes in opposite directions. To supply combustion and scavenger air to the combustion chamber 3, an inlet port 5 is provided and arranged to be uncovered by power piston 2a near the end of its power stroke and after an exhaust port 6 has been uncovered by power piston 2 substantially at the end of its power stroke. Since the particular free piston machine is intended to be employed as a gas generator for driving a gas turbine or the like, exhaust port 6 is connected to a delivery pipe 7 for conveying the hot exhaust gases to said turbine (not shown). The inlet port 5 is connected to a duct 8 adapted to be supplied with air compressed by the free piston machine itself, as will be pointed out.

To the opposite respective ends of the two power pistons are attached, in coaxial relationship therewith, two larger air compressor pistons 9, 9a slidably mounted in suitable bores in the casing. As power pistons 2, 2a are driven through their power strokes, pistons 9, 9a are advanced in the direction of respective air compressing chambers 10 at their one side, compressing air, previously admitted thereto via respective inlet valves 11, for discharge into the duct 8 via respective discharge valves 12.

Attached to the air compressor pistons 9, 9a opposite power pistons 2, 2a and in coaxial relationship therewith, are two direct bounce pistons 13, 13a, respectively, which are advanced in the direction of respective direct bounce chambers 14 formed in the casing by an end wall and suitable bores in which the bounce pistons are slidably guided. Air trapped in the direct bounce chambers 14 is compressed by the direct bounce pistons 13, 13a during the power stroke of the power pistons 2, 2a, and this compressed air in each of said chambers acts as a spring for cushioning the pistons at the end of said power stroke as well as provides stored energy to actuate the pistons through a return stroke. It will be appreciated that the pressure of air in the chambers 10 acting on pistons 9, 9a may also partially aid in return of the entire piston assemblages.

During the return stroke of the power pistons 2, 2a, as substantially effected through the bounce pistons 13, 13a, the air compressor pistons 9, 9a are caused to move in the direction of respective reverse bounce chambers 15, compressing air trapped therein, and by expansion of said air at the end of said return stroke, aiding the power pistons 2, 2a to repeat their power strokes as above described, compressing air admitted to the chambers 10 during said return stroke.

The two piston assemblages are connected together for symmetrical movement by two oppositely arranged toothed racks 17 and 18 connected at one end to the air compressor pistons 9, 9a, respectively, and operatively connected to each other by a meshing pinion 19 arranged to rotate on a fixed axis.

The two direct bounce chambers 14 are connected one with the other by way of ports 20 and chambers 21 in the casing, and a pipe 22 connecting said chambers 21. The pipe 22 is adapted to be connected to means (not shown) for regulating the amount of air in the direct bounce chambers 14 to alter the running characteristics of the free piston machine for reasons which are of no concern to the present invention.

The two reverse bounce chambers 15 are connected one with the other by way of a pipe 25. During starting of the free piston machine, as will be described hereinafter, the pipe 25 is adapted to be supplied with compressed air from an operator's control device 26 mounted on a pipe bracket 27 and having an operator's handle 26a, by way of passages 29, 29a in said bracket, the former passage being connected to an outlet port 30 in said control device.

One or more starting valve devices 31 are associated with the casing of the free piston machine for each reverse bounce chamber 15, each starting valve device comprising a vent valve 32 arranged to open inwardly of said chamber for establishing a communication from said chamber to atmosphere by way of a port 33, and a spring chamber 34 which is open to atmosphere via a port or ports 35 in the casing of each device. A spring 36 in each valve device 31 is arranged

to urge the valve 32 toward a normally closed position, and a piston in each device connected to said valve is arranged to be operated by fluid under pressure supplied to a chamber 38 to open said valve against action of said spring. The chambers 38 in all of the starting valve devices are connected to a common control pipe 39 which in turn is adapted to be connected to control means (not shown) for controlling supply and release of fluid under pressure thereto during starting and warm-up of the free piston machine, as will be described hereinafter.

According to the invention, a fluid pressure operated valve device 40 is provided interposed in the communication between the operator's control valve device 26 and the pipe 25 connected to the reverse bounce chambers 15 in the free piston machine. The valve device 40 comprises a casing 41 removably mounted on the pipe bracket 27. The casing 41 is provided with a chamber 42 open at one end to the passage 29 at one side of a valve seat 43 which is disposed in said chamber. At an opposite side of valve seat 43, the chamber 42 is open to the passage 29a connected to pipe 25. Disposed in chamber 42 is a normally unseated valve 44 arranged for engagement with seat 43 to close off passage 29 from passage 29a.

The valve 44 is operatively connected to a stem 45 which extends through an opening in a casing partition wall 46 separating chamber 42 from a spring chamber 47. Chamber 47 is open to atmosphere via a port 48 in casing 41, and to prevent leakage of fluid under pressure from chamber 42 past stem 45 into said chamber 47, a sealing ring is disposed in a groove in the opening through the partition wall 46 for slideable sealing contact with the outer surface of said stem. A compression spring 49 is disposed in chamber 47 interposed between the partition wall 46 and a piston 50 which is operatively connected to the stem 45 and exposed to said chamber on its one side. At the opposite side of piston 50 there is a pressure chamber 51 which is adapted to be supplied with fluid under pressure for causing movement of said piston in the direction of chamber 47 to close valve 44. Pressure chamber 51 is connected to the control pipe 39 by way of a passage 52 in the casing 41, a registering passage 52a in pipe bracket 27, and a pipe 53, so that fluid under pressure supplied via said control pipe 39 for effecting opening of vent valves 32 will also at the same time be supplied to said pressure chamber 51 to effect closure of valve 44 for cutting off communication between the reverse bounce chambers 15 and the source of fluid under pressure in passage 29.

Prior to starting the free piston machine, the operator's lever 26a of the operator's control device 26 will be moved to stop position (Fig. 2), if not already in such position, in which position means (not shown) comprised in the control apparatus are so conditioned as to assure that the piston assemblages will be disposed in innermost rest positions, in which they are shown in the drawing, with chambers 14, 10, 15 in said machine, chambers 38 in starting valve devices 31, and chamber 51 in valve device 40 all open to the atmosphere. Vent valves 32 in devices 31 are thus closed by springs 36 and valve 44 in device 40 is opened by spring 49.

In effecting normal starting of the free piston machine, described in detail in the aforementioned application, the operator's handle 26a of device 26 is moved to "Start" position, shown in

Fig. 2, whereupon fluid under pressure is initially supplied via port 30 to passage 29, thence to passage 29a and pipe 25 to the reverse bounce chambers 15. Pressure of fluid thus supplied to the reverse bounce chambers 15 and acting on one face of the pistons 9, 9a is thereby increased sufficiently to cause the piston assemblages to move outwardly; said pistons 9, 9a moving in the direction of respective chambers 10, and after closure of inlet valves 11, thus causing air previously admitted to said chambers to be displaced at slight compression into the duct 8 via the discharge valve devices 12; pistons 13, 13a moving in the direction of respective direct bounce chambers 14 to extreme outer positions; and pistons 2, 2a moving outwardly and consecutively uncovering, respectively, the exhaust port 6 and the inlet port 5, thus allowing air from duct 8 to flow into the combustion chamber 3, sweeping any stale air from said chamber out through said port 6. At the time that the pistons 13, 13a reach their outermost or starting positions, automatic means (not shown) are rendered responsive to effect supply of fluid at a chosen pressure to the direct bounce chambers 14 for charging same therewith. After the direct bounce chambers 14 have become fully charged, automatic means (not shown) are automatically rendered responsive to effect supply of fluid under pressure to the fluid pressure operated starting valve devices 31 via control pipe 39 to cause the vent valves 32 to be opened suddenly. Opening of vent valves 32 opens the reverse bounce chambers 15 to the atmosphere via ports 33, thus suddenly reducing pressure of fluid acting on the respective faces of the pistons 9, 9a, and thereby allowing the fluid under pressure with which the direct bounce chambers 14 were charged to expand against the pistons 13, 13a and cause inward movement of the piston assemblages; pistons 9, 9a moving in the direction of the reverse bounce chambers 15; and pistons 2, 2a moving through a compression stroke in the direction of the common combustion chamber 3, covering ports 5, 6 and compressing air thereby trapped in chamber 3. At some point in the inward stroke of the piston assemblages, by timing means (not shown) comprised in the control apparatus, fluid under pressure is vented from the control pipe 39 to allow the vent valves 32 to close before the pistons 9, 9a reach their innermost extreme positions so that during subsequent movement, pressure of fluid in the reverse bounce chambers will build up. Substantially at the time that the power pistons 2, 2a reach their inner dead-center positions, the air in the combustion chamber 3 is compressed sufficiently to be of sufficiently high temperature to ignite fuel injected into said chamber from nozzle 4. By burning of the fuel in the combustion chamber 3, hot expansible gases are generated which, acting on the power pistons 2, 2a, together with the pressure of fluid in the reverse bounce chambers 15 acting on pistons 9, 9a, causes the piston assemblages to move outwardly. Outward movement of the piston assemblages at this time effects compression of fluid under pressure trapped in the direct bounce chambers 14 for thereby storing energy to be expended in effecting subsequent inward stroke of said assemblages; effects displacement of air admitted to chambers 10 into the duct 8 where same may be compressed to greater or less degree; and effects exhaust of combustion gases from the combustion chamber 3 through the port 6 upon being uncovered by piston 2 and subsequent

scavenging and resupply of combustion air from duct 8 via port 5 upon its being uncovered by piston 2a. By expansion of compressed fluid in the direct bounce chambers 14, the piston assemblages are again caused to travel inwardly, with vent valves 32 remaining closed, to again compress combustion air in the chamber 3 for burning fuel for the return stroke, while pressure of fluid in the reverse bounce chambers 15 is maintained for aiding said return. If the machine is running smoothly, the piston assemblages automatically repeat their inward and outward strokes in the manner above described, and the control lever 26a of the operator's control device 26 is moved to running zone, indicated in Fig. 2, for effecting control of pressure of fluid in the reverse bounce chambers 15 and direct bounce chambers 14 to change operating conditions of the machine for reasons of no concern to the present invention.

If, however, at time of starting, with the operator's control lever 26a in "Start" position and during the initial inward stroke of the piston assemblages for actuating the power pistons 2, 2a through an initial compression stroke to compress combustion air in chamber 3, due to low initial temperature of the lubricant on the cylinder walls, for example, the viscous drag of said lubricant may so slow down said assemblages, together with the restraining action of pressure of fluid trapped in the reverse bounce chambers 15 after closure of vent valves 32, that compression of air in the chamber 3 will be insufficient to cause ignition of fuel therein, in which case the machine does not start, or it may make a few strokes after an initial ignition and then die. To obviate any such difficulty in starting, in the control apparatus disclosed in the aforementioned application, means are provided for effecting a continuous supply of fluid under pressure to the control pipe 39, thence to the pressure chambers in the starting valve devices 31 for causing the vent valves 32 to be held open, so that the above-mentioned restraining action of pressure of fluid in the reverse bounce chamber 15 is thereby eliminated. With the vent valves 32 thus held open the piston assemblages will continue to oscillate as in normal running, and after the machine has been allowed to warm up sufficiently, it is stopped and restarted in the normal manner above described.

According to the invention, when fluid under pressure is supplied to the control pipe 39 for opening the vent valves 32 in the starting valve devices 31, it will also flow from said control pipe to pipe 53 and thence through passage 52a in pipe bracket 27, and the registering passage 52 in casting 41 of valve device 40 into chamber 51 thereof. Pressure of fluid thus supplied to chamber 51 will act on piston 50 to overcome action of spring 49 and move in the direction of the chamber 41, carrying the attached stem 45 and valve 44 with it until said valve engages the seat 43, whereupon further movement in this direction ceases. With the valve 44 thus closed, communication is closed between the passage 29 connected to the outlet port 30 of control device 26, and the passage 29a connected via pipe 25 to the reverse bounce chambers 15 in the free piston machine 1. It will be appreciated that closure of valve 44 will be effected substantially at the same time that vent valves 32 are caused to open, so that particularly during warm-up of the machine, much compressed air from the operator's control device will be saved.

Summary

It will thus be seen that I have provided means particularly adapted for use with control apparatus of the type disclosed in the aforementioned application which is automatically operative, when the vent valves are opened, to vent fluid under pressure from reverse bounce chambers in the free piston machine, to close off communication between the source of fluid under pressure and said chambers, thereby effecting considerable saving in fluid under pressure during starting and warm-up of said machine.

Having now described the invention, what I claim as new and desire to secure by Letters Patent, is:

1. The combination with an internal combustion free piston engine comprising a casing having a reverse bounce chamber, a fluid pressure supply port and a fluid pressure exhaust port opening thereto, of starting control apparatus for said engine comprising an operator's control lever having a start position and means operable by said lever in said start position to establish a fluid pressure supply communication to said supply port, interlock means for closing said supply communication from said operator's control device to said reverse bounce chamber, vent valve means operable to establish a fluid pressure release communication between said exhaust port and the atmosphere, and means connecting both said interlock means and said vent valve means together for operation in unison.

2. The combination with an internal combustion free piston engine comprising a casing having a reverse bounce chamber, a fluid pressure supply port and a fluid pressure exhaust port opening thereto, of starting apparatus for said engine comprising an operator's control device operable to establish a fluid pressure supply communication for conveying fluid under pressure to said fluid pressure supply port to start said engine, vent valve means operable by fluid under pressure to open said exhaust port to atmosphere, and interlock means responsive to supply of operating fluid under pressure to said vent valve

means to interrupt said supply communication between said operator's control device and said supply port.

3. The combination with an internal combustion free piston engine comprising a casing having a reverse bounce chamber, of starting means for said engine comprising an operator's control device operable to supply fluid under pressure to said reverse bounce chamber to start said engine, vent valve means operable by fluid under pressure to vent said reverse bounce chamber to atmosphere, and interlock means responsive to supply of operating fluid under pressure to said vent valve means to interrupt supply of fluid under pressure from said operator's control device to said reverse bounce chamber.

4. The combination with an internal combustion free piston engine comprising a casing having a reverse bounce chamber open to a fluid pressure supply conduit, of an operator's control device operable to supply fluid under pressure to said supply conduit, vent valve means responsive to supply and release of fluid under pressure to a first chamber to open and close, respectively, communication between said reverse bounce chamber and atmosphere, interlock valve means responsive to release and supply of fluid under pressure to a second chamber to establish and disestablish, respectively, communication through said supply conduit, and control circuit means connected to said first and second chambers for conveying fluid under pressure simultaneously to both said first chamber and said second chamber and simultaneously from both said first chamber and said second chamber.
